GUIDE AND WASH-DOWN SHOE FOR WELL CASINGS

Reuben C. Baker, Coalinga, Calif., assignor to
 Baker Oil Tools, Inc., Huntington Park, Calif.,
 a corporation of California

Application July 19, 1937, Serial No. 154,454

5 Claims. (Cl. 166—9)

This invention relates to casing deep oil wells and particularly pertains to an improved guide and wash-down shoe for well casings.

In running in a well casing into a deep oil well bore it is necessary to guide the lower end of the casing past obstructions to prevent it from "hanging up". When bridges are encountered in the bore it is necessary to create a washing action at the lower end of the well casing to wash the same out. This is accomplished by pumping a washing fluid downwardly through the lower end of the casing. Also, it is sometimes advisable to pump a washing fluid downwardly through the lower end of the casing and thence upwardly around the casing to wash out the annular space between the casing and bore to clean out this space for the reception of later placed cement. This insures that a perfect cement seal between the casing and the wall of the bore will be effected.

It is the principal object of my present invention to provide an improved guide and wash down shoe for well casings, by means of which the above described operations may be efficiently performed.

The invention is exemplified in the following description and illustrated by way of example in the accompanying drawing, in which:

Fig. 1 is a view in central vertical section through a device embodying the preferred form of my invention and disclosing the same connected to the lower end of a string of well casing.

Fig. 2 is a view in side elevation of the device with the casing shoe removed to more clearly disclose the construction of the cementitious plug in the casing shoe.

Fig. 3 is a plan view of the device shown in Fig. 1.

Fig. 4 is a view in central vertical section and partly in elevation of a second embodiment of my invention.

Referring more particularly to the accompanying drawing, 10 indicates a well casing and 11 a cylindrical member, which in this instance is illustrated as a casing shoe which may be threaded or otherwise attached to the lower end of the casing 10 prior to the time that the same is run in the well bore.

Cast within the shoe and securely anchored thereto is a cementitious plug 12. It will be seen that the plug 12 is anchored to the shoe 11 by means of anchoring grooves 14 formed in the interior surface of the shoe 11. The lower end of the cementitious plug 12 projects from the lower end of the casing shoe 11, and at the point that it emerges from the shoe it is of the same

diameter as the exterior diameter of the shoe so that no projecting shoulder will occur. From this point the plug is tapered or rounded downwardly and inwardly so as to form a guide end 15 at the lower end of the casing shoe 11. This guide-shaped lower end 15 aids in guiding the lower end of the casing past obstructions in the bore or in the casing within which the present casing 10 is to be run through.

Formed longitudinally through the plug 12 on its axis is a fluid conducting passageway 16 which is common in guide shoes of this type to enable fluid to be pumped downwardly through the lower end of the casing, and likewise to enable cement to be ejected from the lower end of the casing under pressure during the cementing operation.

In addition to the fluid conducting passageway 16, I have provided, in the form of the invention shown in Figs. 1 to 3, inclusive, a plurality of fluid conducting passageways 17. In the present instance I have shown three of these passageways spaced equal distances apart about the periphery of the plug 12, which passageways are formed in the plug closely adjacent to the outer circumference thereof, and they extend from the upper end of the plug 12 through the lower end thereof.

In Figs. 1 to 3, inclusive, I have shown the fluid conducting passageways 17 as being helical so that the washing or other fluid discharged downwardly therethrough will take a swirling course so as to properly distribute the fluid pumped downwardly therethrough about the casing. This not only creates an efficient washing action but likewise creates a very efficient cementing action.

In Fig. 4, I have shown the passageways 17 as being parallel to the axis of the plug and extending from the upper end of the plug through the lower end thereof at the inner periphery of the shoe 11. It is obvious that these passageways likewise evenly distribute the fluid about the casing, and being closely adjacent to the outer periphery of the casing make for a better washing action.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A device of the character described including a hollow cylindrical member adapted to be

- connected to the lower end of a string of well casing, a cementitious plug cast in said member and securely anchored thereto, said plug having a plurality of eccentrically positioned passageways spaced apart circumferentially of the plug and located closely adjacent to the outer circumference of the plug and extending from the upper end thereof through the lower end thereof.
5. A device of the character described including a hollow cylindrical member adapted to be connected to the lower end of a string of well casing, a cementitious plug cast in said member and securely anchored thereto, said plug having a plurality of eccentrically positioned passageways spaced apart circumferentially of the plug and located closely adjacent to the outer circumference of the plug and extending from the upper end thereof through the lower end thereof, said passageways following a helical path from the upper end to the lower end of the plug so as to create a swirling action of fluid ejected from the lower end thereof.
10. A device of the character described including a hollow cylindrical member adapted to be connected to the lower end of a string of well casing, a cementitious plug cast therein and anchored thereto, said plug having a rounded lower guide end extending below the end of the cylindrical member for guiding purposes, said plug having a plurality of fluid conducting passageways extending from its upper through its lower end, said passageways being spaced apart circumferentially of the plug and located closely contiguous to the outer circumference thereof, said passageways following a helical path from the upper through the lower end of the plug to create a swirling action of the fluid as it emerges from the lower end thereof.
15. A device of the character described including a hollow cylindrical member adapted to be connected to the lower end of a string of well casing, a cementitious plug cast therein and anchored thereto, said plug having a rounded lower guide end extending below the end of the cylindrical member for guiding purposes, said plug having a plurality of fluid conducting passageways extending from its upper through its lower end, said passageways being spaced apart circumferentially of the plug and located closely contiguous to the outer circumference thereof, said passageways following a helical path from the upper through the lower end of the plug to create a swirling action of the fluid as it emerges from the lower end thereof.
20. A device of the character described including a hollow cylindrical member adapted to be connected to the lower end of a string of well casing, a cementitious plug cast therein and anchored thereto, said plug having a rounded lower guide end extending below the end of the cylindrical member for guiding purposes, said plug having a plurality of fluid conducting passageways extending from its upper through its lower end, said passageways being spaced apart circumferentially of the plug and located closely contiguous to the outer circumference thereof, said passageways being formed in a straight line parallel to the longitudinal axis of the plug.
25. A device of the character described including a hollow cylindrical member adapted to be connected to the lower end of a string of well casing, a cementitious plug cast therein and anchored thereto, said plug having a rounded lower guide end extending below the end of the cylindrical member for guiding purposes, said plug having a plurality of fluid conducting passageways extending from its upper through its lower end, said passageways being spaced apart circumferentially of the plug and located closely contiguous to the outer circumference thereof, said passageways being formed in a straight line parallel to the longitudinal axis of the plug.
30. A device of the character described including a hollow cylindrical member adapted to be connected to the lower end of a string of well casing, a cementitious plug cast therein and anchored thereto, said plug having a rounded lower guide end extending below the end of the cylindrical member for guiding purposes, said plug having a plurality of fluid conducting passageways extending from its upper through its lower end, said passageways being spaced apart circumferentially of the plug and located closely contiguous to the outer circumference thereof, said passageways being formed in a straight line parallel to the longitudinal axis of the plug.
